ATTORNEY

UNITED STATES PATENT OFFICE.

CHARLES A. BIRCH-FIELD, OF LARCHMONT, NEW YORK.

INDUCTANCE UNIT.

Application filed April 3, 1925. Serial No. 20,443.

This invention relates to improvements in the construction of inductance units, coils or the like finding particular applicability and use in wireless or radio telephony or telegraphic systems.

The object of this invention is to provide inductance units in which there will be a substantial self-contained electromagnetic field or one whose electromagnetic field has substantially no disturbing influence on adjacent apparatus by diminishing to a minimum the external field thereof.

Another object of my invention resides in the provision of inductance units in which the distributed capacity and self-induction is reduced to such an extent so that in their relation to each, the coils will have a resultant radio frequency resistance conducive to giving the system in which they are used more selective and sharper tuning.

A further object of my invention resides in the provision of inductance units whose manufacture entails high degree of simplicity at the same time providing a product which is durable and inexpensive.

A still further object of my invention resides in the provision of a coil which may form the basis for the adjustable or variable coils of primary and secondary fields of a radio system or if desired, the fixed inductance or further one which may also form the basis for the fixed primary and secondary circuit of radio frequency transformer elements or the like.

A still further object of my invention resides in the provision of a new and simple manner of winding inductance units and further in a new and novel frame for winding the same.

To obtain these objects and such further objects as may appear or be hereinafter pointed out, I make reference to the accompanying drawing forming a part hereof, in which:

Fig. 1 is a plan view of a coil frame made in accordance with my invention.

Fig. 2 is a side elevation of the frame shown in Fig. 1.

Fig. 3 is a plan view of a mounted coil.

Fig. 4 is a modification in the form of a transformer.

In the illustration shown, 10 is a frame of insulating material such as a phenolic condensation product, rubber, cardboard, wood, glass or the like made in sheet form of com-

paratively small thickness. This frame has its length and width in such proportions as to be multiples of each other, and in the embodiment shown, the frame is twice the length of the width for a purpose such as will be hereinafter described. The peripheral edges of the frame are formed with slots 11, 12, 13, 14, 15 and 16 and are cut diagonally so that when viewed at any particular point of reference, the two slots will slant in the same direction towards one face.

As shown in the illustration, 11 and 12 will slant towards the front face towards each other. 12 and 13 will slant towards the back face towards each other. 13 and 14 will slant towards the front face towards each other. 14 and 15 will slant towards the back face towards each other. 16 and 11 will slant towards the back face towards each other.

The frame may be for reference purposes divided along vertical and horizontal axes V and H intersecting at O, then the length along the horizontal axis will be twice that of the dimension across the vertical axis. The slots 11, 12, 13, 14, 15 and 16 are positioned so as to have the vertical slots 13, 15, 12, 16 equidistant from the vertical axis and the outside length of the frame which is substantially equal to one-half of the width of the frame.

A frame of this kind adapts itself readily for supporting a conductor which may be wound continuously, and in the illustration shown in Fig. 3, starting at the slot 11 in one corner thereof, there is formed a terminal post 17 forming the anchor for the conducting member 18. Thence the conducting member is positioned in the slot 11 and the winding then proceeds from slot 11 to 12 across the front face, from 12 to 13 across the back face, from 13 to 14 across the front face, from 14 to 15 across the rear face, and thence from 16 to 11 again to make a complete turn. This procedure is repeated as many times as desired in the same direction, after which the other terminal 19 is finally positioned in the binding post 20.

It will thus be observed that two adjacent geometric figures are formed designated 21 and 22 in which the conductors are all positioned at substantially right angles to each other, and as shown, the conductors running from 12 to 13 and 15 to 16 will also cross each other at substantially right angles.

In so winding the conductor upon the frame of the nature described, a current passing through the coil at any instant will produce an electro-magnetic field in the portion described by the geometric figures 21 and 22 which will be substantially in a contradirection to each other. Also as the conductors are positioned at right angles to each other at any point of reference, the self induction will be reduced to a minimum.

Although I have described the frame as having a length as twice that of the width and the slots so formed that substantial squares will be formed, the length of the frame may be multiples of the unit thus described and obtain results which will serve equally the same purpose.

In Fig. 4, I have shown a modification of the device wherein the windings may be shown arranged so as to form an air-core transformer. In this embodiment binding posts P P are shown at the left hand side forming as the terminals of the windings which form the primary circuit, and at the right hand side, the binding posts S—S form the terminal edges of the secondary circuit. The primary wires may be wound so as to be interposed between the secondary windings, or one on top of each other. In the illustration shown, the secondary coil designated by the letter S is shown interposed between the primary wires designated by the letter P.

It will thus be observed that I have provided an inductance unit which may be wound continuously and give maximum inductance in a substantial uni-plane, but by reason of the fact that the current at any instant moment in the two branches of the geometric figures 21—22 are in opposite directions, the flux through the center of each figure will be in opposite directions and will neutralize the other, and it will be further observed that as each adjacent side of the geometric figures is perpendicular to each adjacent side, the self induction will be decreased to the maximum lowest degree.

Units of this type whether used in variable tuning or fixed tuning, due to the stability and neutralized effect, are admirably suited for selective tuning in wireless telegraphy and telephony in a manner which will be obvious to those skilled in the art for purposes of the primary or secondary or tickler coils, parts of variometers or transformers and the like.

I claim:

1. An inductance unit comprising a conductor wound continuously and alternately in substantially parallel planes and forming a plurality of adjacent polygonal figures, the windings of the said figures being in oppo-

site directions and forming an external field of low value and low distributed capacity.

2. An inductance unit comprising a conductor wound continuously and alternately in substantially parallel planes and forming a plurality of interconnected substantially rectangular figures, the adjacent sides thereof being substantially equal.

3. An inductance unit comprising a conductor wound continuously in substantially parallel planes and forming two adjacent polygonal figures having a common point, the windings thereof being in opposite directions and forming an external field of low value.

4. An inductance unit comprising a conductor wound continuously upon a thin frame of a non-conducting material upon opposite sides thereof, in the form of a plurality of rectangular figures delineating substantially a figure 8, the windings on each side being in substantially parallel planes and each equal to the winding on the other side.

5. A transformer comprising a primary conductor wound continuously and alternately in substantially parallel planes and forming a plurality of adjacent geometric figures, the windings thereof being in opposite directions, and a secondary conductor similarly wound interposed between the first named windings.

6. An inductance unit comprising a conductor wound upon opposite sides of a thin frame and continuously in the shape of a plurality of rectangular geometric figures occupying substantially parallel planes and arranged so that the central axis joining such figures is rectilinear.

7. An inductance unit comprising a conductor wound continuously upon a thin frame of non-conducting material, upon opposite sides thereof in the form of a plurality of adjacent rectangular figures, the windings on each side of said frame being in substantially parallel planes and each equal to the windings on the other side, adjacent lengths of conductor being on opposite sides of the frame and rectangularly disposed to each other, with the windings in the adjacent geometric figures oppositely disposed.

8. In a device of the character described, a slotted frame and a conductor wound on both sides thereof and passing through the slots to form a plurality of connected figures of substantially rectangular shape, the windings on one side being substantially rectangularly disposed with respect to the windings on the other side.

In testimony whereof I have hereunto signed my name.

CHARLES A. BIRCH-FIELD.
